UNITED STATES PATENT OFFICE.

CALVIN L. FARRAR, OF LAKECREEK, OREGON

HOUSEHOLD UTILITY DEVICE.

1,256,002.

Specification of Letters Patent. Patented Feb. 12, 1918.

Application filed February 16, 1917. Serial No. 148,986.

To all whom it may concern:

Be it known that I, CALVIN L. FARRAR, a citizen of the United States of America, residing at Lakecreek, in the county of Jackson and State of Oregon, have invented certain new and useful Improvements in Household Utility Devices, of which the following is a specification.

This invention relates to a household utility device and its object is to provide a simple and inexpensive structure adapted to be readily and quickly attached in position above a kitchen sink and in operative relation to the water supply faucets and constructed in such manner that the water from the faucets may be utilized not only in conjunction with the washing and cleansing of articles but the power thereof may also be utilized to operate a water motor from which other articles such as egg beaters, ice cream freezers, bread mixers and the like may be driven.

Further objects and advantages of the invention will be set forth in the detailed description which now follows:

In the accompanying drawing,

Figure 1 is a view partly in front elevation and partly in section of an apparatus constructed in accordance with the invention.

Fig. 2 is a vertical, sectional view through the sink with the apparatus in end elevation, and

Fig. 3 is a detail, sectional view through the casing of the water motor.

Like numerals designate corresponding parts in all of the figures of the drawing.

Referring to the drawing the numeral 5 designates an ordinary kitchen sink, 6 the usual drain board and 7 and 8 the hot and cold water faucets, respectively. As this description proceeds it will be seen that my invention contemplates broadly the provision of a water motor, a tank, means for conducting cold water from the cold water faucet both through the water motor for the purpose of driving the latter and to the aforesaid tank; a connection from the hot water faucet to a rinsing cock and a cleansing element such as a brush or the like disposed in coöperative relation to the tank together with means for supporting the aforesaid elements above a sink and in operative relation to the hot and cold water faucets, I, therefore, wish it to be understood that the particular method of mounting the apparatus is immaterial. However, as illus-

trating an operative construction I have indicated a supporting frame consisting of the standards 9 and 10 the lower ends of which rest upon the bottom of the sink 5. 60 These standards are made in two sections and the sections of the standards are vertically adjustable with relation to each other by means of screws 11 and 12. At the upper end the standard 9 is provided with a laterally open fork 13 adapted to be engaged behind the hot water faucet 7. The upper end of the standard 10 is provided with a horizontal bar 14 that carries a bearing block 15 to which is pivoted a curved lever 16. 70 This curved lever is adapted to be swung over the cold water pipe behind the cold water faucet 8 and carries at its free end a latch 17 that is adapted to engage a nose 18 of a vertical bar 19, the latter being longitudinally adjustable with respect to the bar 14 through the medium of a thumb nut 20 that moves in a slot formed in the bar 14. 75 Connections 21 and 22, which may be of the usual and well-known type, are adapted to connect flexible hose sections 23 and 24 to the hot and cold water faucets, respectively. The hose 24 conducts cold water through a branch pipe 25 to the casing 26 of a water motor, the water being controlled 80 in its passage through said casing by a valve 27. A branch pipe 28 conducts the cold water to a tank 29 and the water passing through the branch pipe 28 is controlled by a valve 30. The pipe 28 is connected to the standard 10 at 31. Said standard is provided with a bearing at 32 for the shaft 33 of the water motor, it being understood that said shaft carries a water wheel 34 within the casing 26. The discharge from the casing 26 is conducted through a pipe 35 to the sink and preferably directly above the drain pipe 36 from said sink. The hot water from the hot water faucet 7 may pass either into the tank 29 through a pipe 37 100 having a controlling valve 38 located therein or it may pass through a pipe 39 to a rinsing faucet 40. One end of the tank is connected at 41 with the standard 9. The tank 29 has a perforated bottom through which the water may be discharged upon a brush 43. This brush is mounted upon a hollow shaft 44 or upon a shaft having a socketed end that is adapted to engage the end of the shaft 33. A latch 45 is pivoted at 46 to the shaft 33 and a spring 47 normally tends to move its end 48 inwardly or into such posi-

tion that it passes through a part of the shaft 44 and engages the shaft 33 to thereby lock these parts in operative relation with each other. A rear splashing shield 49 and 5 a front splashing shield 50 protect the operator from the water splashed by the brush 43. The shields 49 and 50 are provided with hooks 51 which engage keepers 52 carried by the tank 29 so that these shields may 10 readily be lifted from their position.

The operation of this device is as follows: Water being admitted to the casing 26 of the water motor, the shaft 33 will be revolved and consequently rotation will be imparted 15 to the brush 43. By proper manipulation of the valves 30 and 38 water at any temperature may be admitted to the tank 29 and discharged through the orifices 42 upon the rotating brush. Dishes may be quickly and 20 readily washed by holding them in contact with the rotating brush and they may be rinsed by holding them under faucet 40.

A rotative brush mounted as shown and operating in conjunction with the tank 29 is 25 particularly useful for cleaning cut glass because these bristles enter the recesses of articles and get out the dirt that could not be reached by ordinary washing methods. While I have stated that the article may be 30 rinsed by holding the same under the faucet 40 it may be rinsed to equal advantage by holding it below the tank 29 and above the brush.

If desired soap may be placed in the tank 35 29 so as to render all of the water flowing therethrough more or less soapy, though if preferred, independent soaping means may be employed. By using a brush of shorter and heavier bristles the device is well adapted 40 for washing pans, vegetables, etc., and if desired a brush having wire or steel bristles may be substituted for the brush 43 to thereby render it adapted for scouring off very hard substances.

45 By shutting off the water from the tank 29 so that no water flows through the orifices 42 a brush suitable for polishing silver ware may be employed or a polishing head of any suitable construction may be substituted for 50 the brush 43.

By removing the shields 49 and 50 entirely the shaft 33 is rendered readily accessible for any use to which a revolving shaft may be put. For instance in lieu of the brush 43 55 a grind-stone may be mounted upon the shaft 33 by which knives and like articles may be sharpened or any kitchen utensil requiring power may be driven from said shaft. It is unnecessary to enumerate all of 60 these but among them may be mentioned

bread and cake mixers, egg beaters, ice-cream freezers and the like.

It is to be understood that various minor changes may be made in my invention without departure from the spirit thereof. For 65 instance, where the water power is low I may find it desirable to drive the shaft 33 from the water wheel through interposed gears instead of driving this shaft direct but since this is a change that involves no invention but is such a change as any competent mechanic could make upon request, I consider it unnecessary to illustrate the same.

Having described my invention what I 75 claim is:—

1. In a device of the character described the combination with a supporting frame adapted to rest within a kitchen sink, of means carried by said frame for attaching 80 the frame to the hot and cold water faucets, a mixing tank carried by said frame, means for conducting water from both the hot and cold water faucets to said mixing tank, a rotative brush supported beneath the mixing tank and upon which the water from the tank is discharged and means for rotating said brush.

2. In a device of the character described the combination with a supporting frame 90 adapted to rest within a kitchen sink, of means carried by said frame for holding the frame against movement with respect to the sink, a mixing tank carried by said frame, means for conducting water from both the 95 hot and cold water faucets to said mixing tank and upon which the water from the tank is discharged, means for rotating said brush and a pair of shields supported from said tank and disposed upon opposite sides 100 of said brush.

3. A device of the character described comprising a supporting frame, means for securing said supporting frame in operative position with relation to a kitchen sink, a 105 mixing tank carried by said frame, a water motor supported upon said frame, a rotative brush disposed beneath the mixing tank, connections between said brush and the water motor whereby said brush is driven 110 from the water motor, a system of piping supported by the frame and connected to the mixing tank and to the water motor, detachable connections for connecting said system of piping to both the hot and cold water 115 faucets.
